CLAIM

The ornamental design for a housing for a cordless telephone or similar article, substantially as shown and described.

DESCRIPTION

FIG. 1 is a front elevational view of a housing for a cordless telephone or similar article showing my new design;

FIG. 2 is a rear elevational view thereof;

FIGS. 3 and 4 are respectively right and left side elevational views taken from the FIG. 1 orientation;

FIGS. 5 and 6 are respectively top and bottom plan views thereof;

FIG. 7 is a front, top and side perspective view thereof; and

FIG. 8 is a rear, bottom and side perspective view thereof.

The broken line showings in FIGS. 5 and 7 are for environment associational purposes only and form no part of the claimed design.

FIG. 1

FIG. 2

FIG. 3

FIG. 4

FIG. 5

FIG. 6

FIG. 7

FIG. 8
